ROOFING TILE

Fritz Georgi, Dresden, Germany

Application June 1, 1937, Serial No. 145,841
In Germany May 30, 1936

7 Claims. (Cl. 108—10)

(Granted under the provisions of sec. 14, act of
March 2, 1927; 357 O. G. 5)

The present invention relates to a novel roofing tile.

A moulded tile already known has a longitudinal trough debouching into laterally divergent terminal channels adjacent the lowermost or drip edge of the tile. This trough, however, weakens the tile precisely at the place at which external pressure is applied to the covering surfaces, such tiles therefore usually breaking in the direction of the longitudinal axis. Moreover, valley coverings cannot be made with these roofing tiles; the weakened middle of the tile would be unsupported. Such tiles have usually to be made in ram presses and are therefore more expensive. Further, it has been found that the water tends to collect in ridges at the cut lower edge of the tile, irregular drip points being formed, accompanied by creeping of the water upwards on the underside of the tile.

An object of the present invention is to provide a flat tile with swallow tail drip edge and at least one cross channel, in the vicinity of and approximately parallel to said edge, indented in said upper side.

This novel tile is advantageous inasmuch as the water is led away towards the sides, without running towards the middle of the tile and thence creeping upwards on the undersurface. The advantages consist, therefore:

(1) In keeping the water away from the joints and underside;

(2) In increasing the useful life of the tile, as a result of the first advantage;

(3) In the possibility of saving timber, since adequate protection is afforded by a smaller lap, and consequently the supporting laths can be more widely spaced than heretofore. For example, in the case of a single-lapped roof with a slope of 45°, the spacing of the laths can be increased from 28 cm. to 31 cm., and, in the case of a double-lapped roof, from 14.25 cm. to 16.5 cm. The saving amounts to about 10—15% of timber, the saving of tiles and weight being 10—12% in double-lapped roofs and about 15% in single-lapped roofs.

(4) In the possibility of reducing the pitch of the roof as compared with that usual for plain tiles, because the draining action of the tiles according to the invention is greater in the case of flatter roofs.

Since, to the knowledge of the inventor, it has been established that, in the case of every known roofing tile, the lowermost edge of the tile leads to the draining away of the rain water, through the formation of water ridges, and that unde-

sired drip points may thereby occur in the immediate vicinity of the overlapped joints, the object in view is to prevent the formation of such ridges.

Moreover, in the event of unusually heavy 5 downfall, the water may form ridges, even in the case of simple channelled tiles, which ridges, although kept away from the joints, may always lead to an undesired wetting of the overlap.

The keeping of the lowermost edge of the tile 10 free from such water ridges, directly over and beside the overlapped joints, is extremely important.

The present invention includes the further feature of providing, above the apex of the main 15 swallowtail channel, supplementary short channels with a similar course, so that the channels resemble a conventional pine tree in design. The main channel is arranged so that its lower ends run parallel with the ends of the swallowtail drip 20 edge and terminate directly above the desired drip points, the supplementary channels higher up are shorter, and may terminate a few centimetres to right and left of the apex. In this manner a better deflection of the water is obtained, 25 inasmuch as laterally deflected streams of water are formed at the short channels and are led, over the surface of the tile, towards the drip points, so that the bottom edge of the tile remains practically free from running water at 30 the apex of the swallowtail and for a certain distance to right and left of the apex—that is, therefore over the upper visible end of the overlapped joint—even under a very heavy downfall.

This result might, perhaps, also be attained, 35 by a plurality of continuous cross channels, but would have the disadvantage of wetting portions of the lateral joints.

Moreover, in the case of a plurality of continuous channels, the tile would be weakened at such portions of its covering surface as are most exposed to pressure stresses. Such roofing tiles could not be employed as valley coverings, since, in such case, the tile must be divided diagonally, and undesired and unsuitable water pockets 40 would then be formed at the joints.

In the accompanying drawing, by way of example,

Fig. 1 shows one embodiment of the novel tile according to the invention;

Figs. 2 to 6 represent other embodiments of 50 the novel tile, Fig. 2 being a plan of a tile with channels in the aforesaid pine tree relationship,

Fig. 3 a front elevation of the swallowtail end of the tile,

Fig. 4 a section along the line III--III of Fig. 2.
 Fig. 5 a plan of a tile with channels, the apices of which are offset from the central longitudinal line, and

5 Fig. 6 a plan of another tile in which the channels lead from different apices to common drip points.

In Fig. 1 the tile 1 is shaped in such a manner that the two bottom tips 4 and 5 are formed, at 10 the sides, at a distance of half the width of the tile from the longitudinal median line. The tile 1 has a swallowtail drip edge 6. A draining channel 7 is provided adjacent and parallel with the swallowtail edge 6.

15 In Figs. 2 to 6, the tiles are also indicated by 1, their swallowtail ends by 6 and the main channels lying parallel therewith by 7. Supplementary short channels 35 and 36, in pine tree relationship, are shown in Fig. 2. The geometrical location of the apices 37, 38 and 39 of the channels 7, 35 and 36 is in the longitudinal median line of the tile. Supplementary short channels 40 and 41, the apices of which are offset are shown in Fig. 5. The main channel 7 and supplementary channels 42 and 43 of the tile in Fig. 25 6 are confluent at common drip points 44 and 45, remote from the apices 46 and 47 of said supplementary channels.

I claim:—

30 1. A roofing tile having a flat upper surface, a swallowtail drip edge and a cross channel indented in said upper surface in the vicinity of and approximately parallel to said edge.

35 2. A roofing tile having a flat upper surface, a swallowtail drip edge, a main cross channel indented in said upper surface adjacent and approximately parallel to said edge, said channel extending from side to side of the tile, and at least one supplementary swallowtail channel indented in said upper surface above said main channel.

40 3. A roofing tile having a flat upper surface, a swallowtail drip edge, a main cross channel indented in said upper surface adjacent and approximately parallel to said edge, said channel extending from side to side of the tile, and at least one supplementary swallowtail channel indented in said upper surface above said main

channel, the apices of said drip edge and said main and supplementary channels being located in the median longitudinal line of the tile.

4. A roofing tile having a flat upper surface, a swallowtail drip edge, a main cross channel indented in said upper surface in the vicinity of and substantially parallel to said edge, said channel extending from side to side of the tile, and a plurality of supplementary, short swallowtail channels indented in said upper surface above 10 said main channel, the apices of said edge and said main channel being located in the median longitudinal line of the tile and the apices of at least some of said supplementary channels being offset from said line.

15 5. A roofing tile having a flat upper surface, a swallowtail drip edge, a main cross channel indented in said upper surface adjacent and substantially parallel to said edge, said channel extending from side to side of the tile, and a plurality of supplementary, short swallowtail channels indented in said upper surface above said main channel, the apices of said edge, said main channel and an uppermost one of said supplementary channels being located in the median 20 longitudinal line of the tile and the remainder of said supplementary channels being symmetrically offset from said line.

6. A roofing tile having a flat upper surface, a swallowtail drip edge, a main cross channel 30 indented in said upper surface adjacent and substantially parallel to said edge, said channel extending from side to side of the tile, and at least one supplementary channel indented in said upper surface, the apices of said edge and said main 35 channel being located in the median longitudinal line of the tile, the apex of said supplementary channel being located in said line above the apex of the main channel, and the ends of said supplementary channel being confluent with the ends 40 of said main channel at common drip points at the sides of the tile.

7. A roofing tile having a swallowtail drip edge, and a narrow, swallowtail channel extending across its upper surface at a constant, short 45 distance from said edge, said upper surface on both sides of the channel being plane.

FRITZ GEORGI.
